(57) CLAIM

The ornamental design for a bottle for cosmetics as shown and described.

DESCRIPTION

FIG. 1 is a font, top, and right side perspective view of a bottle for cosmetics showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof; and,

FIG. 8 is a cross-sectional view thereof along the line 8-8 in FIG. 7.

The broken lines illustrate portions of the bottle for cosmetics and form no part of the claimed design.
